UNITED STATES PATENT OFFICE.

CARL G. A. ROSEN, OF SAN FRANCISCO, CALIFORNIA.

INTERNAL-COMBUSTION ENGINE.

Application filed February 14, 1924. Serial No. 692,750.

My invention relates to an internal combustion engine of the solid injection type, and relates more particularly to the form of the cylinder head and cooperating end of the piston.

An object of the invention is to provide cooperating means associated with the piston and cylinder which will cause that portion of the air occupying the part of the clearance space directly in the path of the fuel to be more highly compressed than the air in the remaining clearance space.

Another object of the invention is to provide means of the character described which will cause the air, during the completion of the compression stroke, to be projected toward the fuel spray with greatly increased velocity.

The invention possesses other objects and features of advantage, some of which, with the foregoing, will be set forth in the following description of the preferred form of my invention which is illustrated in the drawing accompanying and forming part of the specification. It is to be understood that I do not limit myself to the showing made by the said drawing and description, as I may adopt variations of the preferred form within the scope of my invention as set forth in the claims.

The drawing is a longitudinal sectional view of the cylinder and head portion of an internal combustion engine embodying my invention.

As illustrated, the engine 2 comprises a cylinder 3 having a head 4 at one end thereof and a piston 6 mounted for reciprocation in the cylinder bore. In the present embodiment of the invention, air may be introduced into the cylinder and the exhaust gases discharged therefrom through a passage 11 controlled by a single overhead poppet valve 12 which is coaxial with the cylinder. The valve is associated with a ported sleeve 13 which alternately allows communication of passage 11 with the air inlet and exhaust passages 14 and 15 respectively. Solid injection of fuel into the cylinder is afforded through a suitably operated needle valve 16 from which the fuel is adapted to be sprayed into the head end of the cylinder diametrically thereof.

Centrally disposed in the cylinder head and preferably extending from the passage 11 is a cavity 17 which is adapted to form a large part, if not the largest, of the combustion

chamber of the cylinder. The fuel spray is projected into the combustion chamber through a suitable passage 18 which is formed in the head and arranged to connect the fuel valve discharge orifice with said chamber cavity.

Cooperating means are provided on the piston and cylinder head for causing the greatest compression of air in the cylinder during the completion of the compression stroke to take place in that portion of the combustion chamber in which the fuel spray is most widely distributed and while the fuel particles still possess the desired penetrative energy. Formed in the head end of the piston is a concavity 19 having a base portion 21 of conoidal form and a rim portion 22 of frustro-conical form, the axes of said portions being respectively disposed in oblique and colinear relation with respect to the cylinder axis. The apex of the cone 21 and orifice 23 of the fuel valve are arranged to lie on opposite sides of the cylinder axis. Preferably formed integral with the head 4 is a frustro-conical projection 24 corresponding to said cavity portion 22 and arranged to engage therein when the piston is adjacent the head end of the cylinder. In the present embodiment the cavity 17 extends centrally through the projection 24, and a portion of the fuel passage 18 extends radially through said extension. By reference to the drawing, it will be noted that an annular depression 26 is defined between the projection 24 and the bore wall, and is adapted to receive the correspondingly formed piston rim 27 when the projection 24 extends into the piston cavity 22.

With the engine elements thus constructed and related, the operation during the compression stroke will be substantially as follows: Assuming that a charge of air has been introduced into the cylinder, and the piston is nearing the head 4, the pressure of the air, due to shape of the piston and head, will at any instant be greatest adjacent the walls of the cylinder, since a greater proportional reduction of volume has here been effected. With the air thus unequally compressed, inward movement thereof results, the velocity of said movement increasing to a maximum as the piston continues on said stroke. It will thus be evident that as the piston rim 27 moves into the depression 26, the air will be ejected from said depression at a high velocity through the narrowing

passage defined between opposed sides of the piston cavity 22 and projection 24. The conoidal stream of air thus discharged from said latter passage strikes the walls of the 5 base portion of the piston cavity and is deflected therefrom toward the head cavity 17 so as to intersect the stream of fuel which at this time is introduced into the cylinder. Owing to the peculiar shape of the piston 10 cavity 21 and the movement of the piston, the deflected air is for the most part directed toward a common point in the axis of the fuel stream. In this manner there will be built up at said point a greater air compression 15 and density than that produced in other portions of the clearance space. By adjustment of the fuel nozzle, the fuel stream may be regulated so that when it reaches said air concentration point it will have the necessary 20 distribution with the desired penetrative energy. Owing to the fact that the apex of the piston cavity and the fuel valve orifice lie on opposite sides of the cylinder axis, the air deflected from the piston will, 25 as a whole move obliquely against the stream rather than with it.

I claim:

1. In an internal combustion engine, a cylinder, and a piston reciprocating therein and having at the head end thereof a conoidal depression whose axis forms an acute angle with the axis of the cylinder and whose base opening is symmetrically disposed about the axis of the cylinder.
2. In an internal combustion engine of the solid injection type, a cylinder, a piston mounted for reciprocation therein, and provided in its head end with a concavity having a base portion of conoidal form and a 40 rim portion of frustro-conical form, said base portion and rim portion having their axis respectively obliquely and coaxially disposed with respect to the piston axis, a head at one end of said cylinder, and a frustro-conical projection on said head substantially corresponding to and arranged to lie within said rim portion when the piston is adjacent said head.
3. In a solid injection internal combustion 50 engine, a cylinder, a piston mounted for reciprocation therein and formed in its head end with a coaxial frustro-conical cavity defined by an annular projection having its

outer wall forming a continuation of the outer wall of the piston, and a head at one 55 end of said cylinder having a frustro-conical projection corresponding to and arranged to lie in said cavity when the piston is adjacent said head.

4. In an internal combustion engine of the solid injection type, a cylinder, a piston mounted for reciprocation therein and provided in its head end with a concavity having a base portion of conoidal form and a rim portion of frustro-conical form, said base 65 portion and rim portion having their axes respectively oblique and colinear with respect to the piston axis, a head at one end of said cylinder, a frustro-conical projection on said head substantially corresponding to and arranged to lie within said rim portion when the piston is adjacent said head, a chamber in said projection adapted to form with said conoidal cavity the explosion chamber of the engine, a fuel nozzle adapted to direct the 70 fuel into the cylinder from the side of the latter opposite to that lying adjacent the apex of said base portion, and a passage in said projection through which the fuel may discharge directly from the nozzle to the 75 chamber in said projection when the latter lies within the piston cavity.

5. In an internal combustion engine of the solid injection type, a cylinder, a head at one end of said cylinder provided with an annular projection coaxial with said cylinder, a nozzle from which fuel is adapted to be sprayed into the cylinder, a piston mounted for reciprocation in said cylinder and provided with a concavity adapted to cooperate with said projection to effect at the 85 end of the compression stroke the greatest compression of the air at a point in the direct path of said fuel spray.

6. In an internal combustion engine of the solid injection type, a cylinder, and a piston mounted for reciprocation in said cylinder provided with a conoidal concavity having the center of its base lying in the axis of the piston and its vertex in spaced relation from 90 said axis.

In testimony whereof, I have hereunto set my hand at Oakland, California, this 23rd day of January, 1924.

CARL G. A. ROSEN.
